UNITED STATES PATENT OFFICE.

GUY S. BRANTINGHAM, OF NEW YORK, N. Y.

END PIECE FOR WHEEL-SPOKES.

SPECIFICATION forming part of Letters Patent No. 692,821, dated February 11, 1902.

Application filed May 10, 1901. Serial No. 59,562. (No model.)

To all whom it may concern:

Be it known that I, GUY S. BRANTINGHAM, a citizen of the United States, residing in New York city, in the county of Richmond and State of New York, have invented certain new and useful Improvements in End Pieces for Wheel-Spokes, of which the following is a specification.

This invention relates to wheel construction, and has for an object to provide simple and effective means for securing in place the spokes of a wheel.

In the drawings accompanying the present specification and wherein there is set forth an embodiment of my present invention, Figure 1 is a view of a wheel the spokes of which are connected to the wheel-hub by devices embodying the present improvements. Fig. 2 is a view, upon a somewhat larger scale, of a portion of a wheel-hub, showing a number of spokes connected thereto according to my present invention. Fig. 3 is a similar view of a modified construction. Fig. 4 is a perspective view showing an end piece for a wheel-spoke constructed according to my present invention and a portion of a spoke withdrawn from the position in which it engages therewith.

Similar characters of reference designate corresponding parts in all the figures.

Owing to shrinkage and other causes, as wheels are customarily constructed considerable looseness eventually results at the tenon portions of the spokes, giving rise to the rattling or shaking of the spoke-tenon in its socket. This looseness is prevented to a very large extent from occurring and a simple means provided for the ready and expeditious attachment of a spoke in place by combining with the spoke an end piece constructed according to my present invention. This end piece is preferably made of some durable material resistant to atmospheric changes—such, for instance, as brass, composition, or other non-corrosive and appropriate material.

The invention consists in an end piece (designated in a general way by B) formed from material of this nature and having an appropriate tenon *b* adapted to fit into its receiv-

ing-socket, here shown as being in the wheel-hub C, which may be of wood or metal. The end piece is connected to the wheel-spoke 2 in some effective and appropriate manner. Thus, for instance, the connection between the end piece and the spoke may be a mortise-and-tenon one comprising a mortise or socket 3, formed in the end piece, to which is fitted a tenon 4, formed on the end of the spoke. When slid or otherwise inserted in place, the parts may be secured one to the other in any desired and proper manner, as herein shown a screw 5 passing through the end wall of the socket on the end piece into the tenon portion of the spoke, although, of course, other ways may be employed for securing each individual end piece or the entire series of the same to the respective spokes. The tenon on the end piece is shown of the usual construction—that is, it is furnished with shoulders 6, acting as stops to determine the assembled position of the parts.

It may be desired under some circumstances, especially in a wheel of heavy construction, to mutually support the end pieces one against the other, and for this purpose the end pieces may be made of sufficient dimensions to enable their faces to contact one face on an end piece against the opposite face on a contiguous end piece, as shown particularly in Fig. 3.

A wheel provided with spokes having separate and durable end pieces for their attachment is rendered less liable to rattle and work loose, and therefore is stronger than one in which the tenon portions of the spoke are formed integrally with the spokes, by reason of the fact that the end pieces are practically unacted upon by weather and climatic changes. This construction affords, also, means facilitating the replacement of a defective or broken spoke by a new one, especially when the socket in the end piece is made with an end wall, whereby the tenon portion of the spoke may be readily slid into position from the side of the wheel, as indicated in Fig. 4.

Having described my invention, I claim—

1. A spoke having in combination an end piece provided with a projecting tenon for 100

- holding the spoke in the wheel-hub, said tenon having side shoulders impinging against the exterior of said hub.
2. A spoke having in combination an end piece made of resistant and durable material and provided with a projecting tenon for holding the spoke in the wheel-hub, said tenon having side shoulders impinging against the exterior of said hub.
- 10 3. The combination with a spoke, of an end piece to which the spoke is secured and which is provided with a projecting tenon for holding the spoke in the wheel-hub, and means for securing the spoke to a side wall of the end piece.
- 15 4. The combination of a spoke and an end piece to which the spoke is mortised, the end piece having a projecting tenon for holding the spoke in the wheel-hub, and also having side shoulders impinging against the exterior of said hub.
- 20 5. The combination of a spoke, an end piece provided with walls on three sides and open on the fourth side whereby the end piece may be fitted to the spoke by sliding the two together transversely to the axis of the spoke, and a fastening device extending through a wall of the end piece and into the spoke for securing the two together.
- 25 6. The combination with a plurality of spokes, of end pieces each provided with walls on three sides but open on the fourth side, said end pieces being secured to the respective spokes and contacting one with the other
- 30 and mutually supporting each other when in place, and having projecting tenons for holding the spokes in place.
7. The combination with a plurality of spokes, of end pieces each provided with walls on three sides but open on the fourth side, said end pieces being secured to the respective spokes and contacting one with the other and mutually supporting each other when in place, fastening devices which pass through the walls of the respective end pieces and into the corresponding spokes for securing the parts together, and tenons upon the end pieces for holding the spokes in place.
8. The combination of a spoke provided with a tenon, an end piece having an undercut mortise for receiving the tenon of the spoke and which is open on one of its four sides, means for securing the spoke to the end piece, and a tenon on the end piece for holding the spoke in place.
9. The combination of a spoke provided with a tenon, an end piece having a mortise open upon one of its four sides for receiving the tenon of the spoke, a screw passing through a wall of the mortise for securing the spoke and the end piece together, and a tenon on the end piece for holding the spoke in place.
